**BETA-(CYCLIC AMINO)-ALPHA-HYDROXY-
ALKANALS**

John B. Wright and Edward H. Lincoln, Kalamazoo Township, Kalamazoo County, Mich., assignors to The Upjohn Company, Kalamazoo, Mich., a corporation of Michigan

No Drawing. Filed Apr. 30, 1956, Ser. No. 581,272

6 Claims. (Cl. 260—294.7)

The present invention relates to novel β -(cyclic amino)- α -hydroxyalkanals of the formula

wherein

is a cyclic amino radical containing from five to ten ring members, inclusive, which ring members are the said nitrogen atom N, carbon atoms, and not more than one additional hetero atom selected from the group consisting of nitrogen, oxygen and sulfur, and wherein lower-alkyl contains from two to five carbon atoms, inclusive; acetals thereof wherein an acetal radical contains from three to nine carbon atoms, inclusive; and acid addition compounds thereof. Of particular interest are the β -(monocyclic amino)- α -hydroxypropionaldehydes of the formula

wherein

is a monocyclic amino radical containing from five to seven ring members, inclusive, in a single ring, which ring members are carbon atoms and from one to two nitrogen atoms, inclusive; dialkyl acetals thereof wherein alkyl contains from one to four carbon atoms, inclusive; and mineral acid addition compounds thereof. Of most interest are the β -(carbomonocyclic amino)- α -hydroxypropionaldehydes of the formula

wherein

is a carbomonocyclic amino radical containing in a single

2

ring from four to six carbon atoms, inclusive, in addition to said nitrogen atom N; diethyl acetals thereof; and hydrohalic acid addition compounds thereof.

An object of the present invention is to provide the above-defined β -(cyclic amino)- α -hydroxyalkanals and acid addition compounds thereof which have antiviral activity, in particular virucidal activity. Said compounds are useful for virus prophylaxis and decontamination of areas and materials and can readily be applied as the active ingredient in solutions, emulsions and suspensions for spraying, washing, painting, immersing, etc., dusts, aerosols, fumigants, etc., according to methods and procedures well known in the pesticide and disinfectant arts. Usually the acid addition compounds of the present invention are employed for the foregoing purpose since they are more stable and have greater water solubility than the parent free base compounds of this invention, and, therefore, said acid addition compounds are a preferred embodiment of the invention for the foregoing use. The β -(cyclic amino)- α -hydroxy-alkanal acetals of the present invention are useful for the production of the alkanal free bases and acid addition compounds thereof of the present invention. Other objects of the present invention, and uses of the novel compounds thereof, will be apparent to one skilled in the art.

Efficacy of the present antiviral compounds is illustrated by Table I which shows the typically superior results of representative compounds obtained in the well-known *in ovo* survival test for antiviral potency, employing Newcastle's virus (NJ-KD strain) and influenza A virus (PR8 strain) as illustrative viruses. In the test method used to obtain the data in Table I any particular test compound, is dissolved in water or suspended in water-carboxymethyl cellulose, depending on the degree of water solubility. A known volume of such a solution or suspension containing a known concentration of the test compound is injected into the allantoic sac of ten-day fertile eggs, using the technique described by Beveridge and Burnet, Medical Research Council, Special Report Series No. 256, "The Cultivation of Viruses and Rickettsiae in the Chick Embryo," London, His Majesty's Stationery Office, 1946. The test compound is usually administered at or slightly less than the maximum tolerated dose, i.e., the greatest amount which when similarly administered is found to cause no deaths in similar eggs during a 216-hour incubation period. The same volume of the same menstruum without test compound is injected into similar eggs as a control. About fifteen minutes later all eggs, test and control, are inoculated with a virus suspension containing approximately fifty times the LD₅₀ dosage of virus; one LD₅₀ is that amount which kills fifty percent of virus-infected embryonated eggs. The eggs are incubated at 37 degrees centigrade. Survivorship is determined by candling the eggs at eight-hour intervals during a 216-hour period. The protection afforded by a test compound is conveniently expressed thus: percent survivorship of treated eggs after 216 hours (e.g. ninety percent) minus percent survivorship of control eggs after 216 hours (e.g. five percent) equals the protective index (e.g. 85), the maximum protective index value being 100. The test compounds listed in Table I, therefore, are highly potent antiviral agents.

3 TABLE I

Test Compound	Formula	Milli- grams per egg	Protective Index	
			New- castle's Virus	Influenza A Virus
<chem>CC(C)C1CC(C)C(NCC(O)C=O)C1</chem>		2.0	46	-----
<chem>CC(C)C1CC(C)C(NCC(O)C=O)C1</chem>		1.0	22	26
<chem>CC(C)C1CC(C)C(NCC(O)C=O)C1</chem>		4.0	-----	31
<chem>C1=CC=CC=C1</chem>		4.0	43	-----

The β -(cyclic amino)- α -hydroxyalkanals of the present invention are suitably prepared by reaction of an acid addition compound thereof with a base, e.g. sodium hydroxide, sodium carbonate, calcium carbonate, etc., in an aqueous or aqueous organic solvent, followed by extraction of the free base with an organic solvent, drying of the solvent extract, and evaporation of the organic solvent. The acid addition compounds of the present invention are prepared by reaction of the parent free base or preferably a derivative thereof, e.g. an acetal thereof, preferably the diethylacetal, with an acid. Suitable acids are hydrochloric acid (especially preferred), hydrobromic acid and other hydrohalic acid, sulfuric acid, phosphoric acid, and other mineral acid, acetic acid, formic acid, benzoic acid, trichloroacetic acid, succinic acid, maleic acid, citric acid, tartaric acid, phenylacetic acid, oxalic acid, furoic acid, α - and β -cyclopentylpropionic acid, α - and β -phenylpropionic acid, and other acids, particularly those having a pK_a value below five, the pK_a value being a common measure of acid strength (Moeller, "Inorganic Chemistry," John Wiley and Sons, Incorporated, New York, New York, 1952, pages 313-315). The β -(cyclic amino)- α -hydroxyalkanals or preferably a derivative thereof, e.g. an acetal, preferably the diethyl acetal, of the present invention are prepared by reaction of a cyclic secondary amine, the amino nitrogen being in the ring, with an α , β -epoxyalkanal or preferably a derivative thereof, e.g. an acetal, preferably the diethyl acetal, which epoxy compound in turn is prepared from the corresponding α , β -alkenal or derivative thereof, e.g. an acetal, preferably the diethyl acetal. These reactions can be illustrated, using the preferred diethyl acetal derivative, by the equation

While the β -(cyclic amino)- α -hydroxyalkanal diethyl acetal is the preferred acetal of the present invention, the dipropyl acetal, dibutyl acetal, dimethyl acetal, ethylene acetal, 1,2-propylene acetal, 1,3-propylene acetal, 1,2-butylene acetal, etc. also are included within the scope of the invention.

The following examples are illustrative only and are not to be construed as limiting the scope of the present invention.

Example 1

In a 100-milliliter flask fitted with a reflux condenser is placed a solution of 29.2 grams (0.20 mole) α , β -epoxy-

propionaldehyde diethylacetal, seventeen grams (0.20 mole) piperidine and three milliliters methanol. After a few minutes the solution boils quite vigorously and becomes yellow in color. After the boiling subsides the solution is heated on the steam-bath for two hours. The orange reaction mixture is distilled through a ten-inch, glass-helice-packed column. The product, β -piperidino- α -hydroxypropionaldehyde diethylacetal

boiling point 143-145 degrees centigrade at 13.5 millimeters pressure, is collected as a pale yellow liquid in a yield of 41 grams (89 percent); n_{D}^{25} 1.4550.

Analysis.—Calcd. for $\text{C}_{12}\text{H}_{25}\text{NO}_3$: C, 62.30; H, 10.89; N, 6.06. Found: C, 62.20, 62.45; H, 10.99, 10.80; N, 6.06, 6.14.

In the same manner β -piperidino- α -hydroxypropionaldehyde dimethyl acetal, dipropyl acetal, ethylene acetal, and dibutyl acetal are prepared from the corresponding α , β -epoxypropionaldehyde acetal.

Example 2

A solution of seventeen grams (0.074 mole) β -piperidino- α -hydroxypropionaldehyde diethylacetal and 150 milliliters of ten percent hydrochloric acid is prepared and warmed on the steam-bath for one hour. The pale yellow solution is concentrated on the steam-bath at reduced pressure. The pale yellow, solid material is dried with benzene and crystallized from 225 milliliters ethyl alcohol and 225 milliliters ethyl acetate. The white crystalline material is filtered and washed with ether. The product, β -piperidino- α -hydroxypropionaldehyde hydrochloride

melting point 155.5-156.5 degrees centigrade, is collected in a yield of nine grams (64 percent). On recrystallization from 150 milliliters ethyl alcohol and 100 milliliters ethyl acetate, the product, melting point 156-157 degrees centigrade, is obtained in a yield of 7.5 grams (52.5 percent).

Analysis.—Calcd. for $\text{C}_8\text{H}_{28}\text{ClNO}_2$: C, 49.61; H, 8.33; Cl, 18.31. Found: C, 49.80; H, 8.28; Cl, 18.37.

Substitution of hydrobromic acid or sulfuric acid for the hydrochloric acid in the foregoing procedure provides β -piperidino- α -hydroxypropionaldehyde hydrobromide and sulfate, respectively.

Example 3

To a solution of β -piperidino- α -hydroxypropionaldehyde hydrochloride in water is added the theoretical

amount of 0.1 normal aqueous sodium hydroxide solution required to neutralize the hydrochloric acid. The resulting aqueous solution is extracted repeatedly with methylene chloride, and the extracts are dried over anhydrous sodium sulfate. Evaporation of the solvent under reduced pressure from the dried methylene chloride extracts provides β -piperidino- α -hydroxypropionaldehyde free base

which decomposes on standing for several days. Treatment of freshly prepared free base with the theoretical amount of acetic acid provides β -piperidino- α -hydroxypropionaldehyde acetate

In the same manner other acid addition compounds of β -piperidino- α -hydroxypropionaldehyde are prepared including the benzoate, furoate, propionate, phenylacetate, and β -cyclopentylpropionate.

Example 4

A mixture of 35.49 grams (0.3008 mole) of benzimidazole, 43.8 grams (0.300 mole) of α, β -epoxypropionaldehyde diethylacetal and 100 milliliters of ethanol is heated on a steam-bath with stirring for three and one-half hours and then allowed to stand overnight. The mixture is then concentrated in vacuo to a thick reddish-brown liquid. To the residue is added fifty milliliters of acetone and then Skellysolve B (mixture of hexanes) is added at the boiling point until the solution becomes turbid. The solution is placed in the refrigerator and the solid that precipitates is removed by filtration; weight 60.2 grams; melting point 76-85 degrees centigrade. The crude material is purified by boiling it with 500 milliliters of anhydrous ether. There is obtained 41.7 grams (53 percent) of a white crystalline solid melting at 90.2 degrees centigrade. One recrystallization from ether-acetone (500:1) gives β -(1-benzimidazolyl)- α -hydroxypropionaldehyde diethylacetal of the formula

and melting at 91.5-93 degrees centigrade; weight 34.5 grams.

Analysis.—Calcd. for $\text{C}_{14}\text{H}_{20}\text{N}_2\text{O}_3$: C, 63.61; H, 7.63; N, 10.60. Found: C, 63.72; H, 7.42; N, 10.57.

Example 5

To a solution of 7.13 grams of concentrated hydrochloric acid in 19.2 milliliters of water is added 17.3 grams (0.066 mole) of β -(1-benzimidazolyl)- α -hydroxypropionaldehyde diethylacetal. The solution is heated on a steam-bath with stirring at eighty degrees centigrade for one-half hour. During the heating period the solution develops a pink color. The air above the solution is swept out with nitrogen and the solution is allowed to stand for about two weeks. During this period a white solid precipitates slowly from the solution. The solid β -(1-benzimidazolyl)- α -hydroxypropionaldehyde hydrochloride of the formula

is removed by filtration and washed with a small amount (ten milliliters) of ethanol; weight 7.49 grams (51 percent); melting point 152 degrees centigrade with decomposition after starting to discolor at 142 degrees centigrade.

Analysis.—Calcd. for $\text{C}_{10}\text{H}_{11}\text{ClN}_2\text{O}_2$: Cl, 15.64; N, 12.36. Found: Cl, 15.09; N, 12.08.

Treatment of the hydrochloride obtained above with base according to the procedure of Example 3 provides the free base, β -(1-benzimidazolyl)- α -hydroxypropionaldehyde.

Example 6

In a one-liter, round-bottomed flask is prepared a solution of 219 grams (1.5 moles) α, β -epoxypropionaldehyde diethylacetal, 107 grams (1.5 moles) pyrrolidine and three milliliters methanol. A short time after the preparation of the solution a vigorous reaction takes place requiring cooling in an ice-bath to keep the reaction under control.

After the reaction has subsided the mixture is warmed on a steam-bath for 45 minutes. The amber residual oil is distilled under reduced pressure through a ten-inch, glass-helices-packed column. The β -pyrrolidino- α -hydroxypropionaldehyde diethylacetal

product, boiling point 88-90 degrees centigrade at 0.5 millimeters pressure, is collected as a colorless oil; yield 233 grams (71 percent); $n_{D}^{25.5}$ 1.4522.

Analysis.—Calcd. for $\text{C}_{11}\text{H}_{23}\text{NO}_3$: C, 60.80; H, 10.67; N, 6.45. Found: C, 61.17; H, 10.58; N, 6.38.

In the same manner β -pyrrolidino- α -hydroxypropionaldehyde dimethyl acetal, ethylene acetal, 1,2-propylene acetal and dibutyl acetal are prepared from the corresponding α, β -epoxypropionaldehyde acetal.

Example 7

In a one-liter, three-necked, round-bottomed flask fitted with mechanical stirrer and reflux condenser is prepared a solution of 130.2 grams (0.60 mole) β -pyrrolidino- α -hydroxypropionaldehyde diethylacetal and 600 milliliters ten percent hydrochloric acid. The solution is heated on a steam-bath with continuous stirring for one and one-half

hours, then concentrated on the steam-bath under reduced pressure, and the residual gum is dried with toluene. The reddish oily gum is dissolved in 350 milliliters hot ethyl alcohol and then diluted with 350 milliliters ethyl acetate and 100 milliliters ether. The pale cream-colored

crystalline material, melting point 136-137 degrees centigrade, is collected in a yield of seventy grams (65 percent). The β -pyrrolidino- α -hydroxypropionaldehyde hydrochloride

after recrystallization twice from ethyl alcohol and ether melts at 138-139 degrees centigrade; weight, 53 grams (fifty percent).

Analysis.—Calcd. for $\text{C}_7\text{H}_{14}\text{ClNO}_2$: C, 46.80; H, 7.85; Cl, 19.74; N, 7.80. Found: C, 47.39; H, 7.93; Cl, 19.49; N, 7.93.

Treatment of the hydrochloride obtained above with base according to the procedure of Example 3 provides the free base, β -pyrrolidino- α -hydroxypropionaldehyde

Reaction of this base (freshly prepared) with phenylacetic acid provides β -pyrrolidino- α -hydroxypropionaldehyde phenylacetate

In the same manner other acid addition compounds are prepared including the citrate, succinate, propionate, furoate, β -cyclopentylpropionate, etc.

Example 8

Following the procedure of Examples 1-7 there are

prepared β -(1-indolyl)- α -hydroxyvaleraldehyde, the diethyl acetal and hydrochloride thereof; β -morpholino- α -hydroxy- α -methyisovaleraldehyde, the ethylene acetal and acetate thereof; β -pyrrolidino- α -hydroxy-isobutyraldehyde, the dibutylacetal and hydrochloride thereof; β -pyrrolino- α -hydroxyisovaleraldehyde, the diethyl acetal and sulfate thereof; β -(1,2,3,4 - tetrahydroquinolino) - α - hydroxypropionaldehyde, the diethyl acetal and phosphate thereof; β - (2-methylpyrrolidino)- α -hydroxypropionaldehyde, the 1,2-propylene acetal and sulfate thereof; β -thiamorpholino- α -hydroxypropionaldehyde, the diethyl acetal and hydrochloride thereof; β -hexamethyleneimino- α -hydroxybutyraldehyde, the dimethyl acetal and hydrobromide thereof; and other β -(cyclic amino)- α -hydroxy-alkanals, acetals and acid addition compounds thereof of the present invention.

It is to be understood that the invention is not to be limited to the exact details of operation or exact compounds shown and described, as obvious modifications and equivalents will be apparent to one skilled in the art, and the invention is therefore to be limited only by the scope of the appended claims.

We claim:

1. Acid addition salts of β -(carbomonocyclic amino)- α -hydroxypropionaldehyde compounds of the formula

wherein

10 is a member of the group consisting of pyrrolidino, 2-methylpyrrolidino, piperidino, thiamorpholino, 1,2,3,4-tetrahydroquinolino, and benzimidazolyl.

15 2. β -Pyrrolidino - α - hydroxypropionaldehyde diethylacetal.

3. β -Pyrrolidino- α -hydroxypropionaldehyde hydrochloride.

4. β -Piperidino- α -hydroxypropionaldehyde diethylacetal.

5. β -Piperidino- α - hydroxypropionaldehyde hydrochloride.

20 6. β -(1-benzimidazolyl)- α -hydroxypropionaldehyde hydrochloride.
